DESIGN FOR AN INSTRUMENT CASE

Lurelle Guild, Darien, Conn., assignor to Weston
Electrical Instrument Corporation, Newark,
N. J., a corporation of New Jersey

Application January 29, 1937, Serial No. 67,341

Term of patent 3½ years

To all whom it may concern:

Be it known that I, Lurelle Guild, a citizen of the United States, residing at Darien, county of Fairfield, State of Connecticut, have invented a new, original, and ornamental Design for an Instrument Case, of which the following is a specification, reference being had to the accompanying drawing, forming part thereof, and wherein:

Fig. 1 is a front elevation of the instrument case, showing my new design; and

Fig. 2 is a side elevation of the same.

I claim:

The ornamental design for an instrument case, as shown.

LURELLE GUILD.
